UNITED STATES PATENT OFFICE.

PATRICK F. GUTHRIE AND THOMAS HAYES, OF NUTLEY, NEW JERSEY.

WASTE FOR BATH-TUBS, BASINS, AND LIKE FIXTURES.

No. 851,513.

Specification of Letters Patent.

Patented April 23, 1907.

Application filed January 13, 1906. Serial No. 295,874.

To all whom it may concern:

Be it known that we, PATRICK F. GUTHRIE and THOMAS HAYES, both citizens of the United States, and residents of Nutley, in the county of Essex and State of New Jersey, have invented a new and Improved Waste for Bath-Tubs, Basins, and Like Fixtures, of which the following is a full, clear, and exact description.

1. The object of the invention is to provide a new and improved waste or outlet for bath-tubs, basins and like fixtures, arranged to insure a free outflow of the water from the bath tub, basin or like fixture, and without danger of the outflowing water becoming air-bound, and to prevent foul air rising in the waste and passing into the room in which the fixture is located, thus rendering the fixture completely sanitary.

2. The invention consists of novel features and parts and combinations of the same which will be more fully described hereinafter and then pointed out in the claims.

3. A practical embodiment of the invention is represented in the accompanying drawings forming a part of this specification, in which similar characters of reference indicate corresponding parts in all the views.

4. Figure 1 is a sectional side elevation of the improvement as applied to a bath tub; Fig. 2 is an enlarged sectional plan view of the improvement, on the line 2—2 of Fig. 1; and Fig. 3 is a similar view of the same, on the line 3—3 of Fig. 1.

5. The lower portion of the stand-pipe A is connected, by a waste-pipe B with a bath tub, basin or similar fixture C, and in the lower end of the stand-pipe A is arranged a valve-seat D leading to the waste-pipe E for carrying the waste water to a sewer or other place of discharge. On the valve-seat D is adapted to be seated a hollow valve F having a tubular valve-stem F' extending up within the stand-pipe A, and provided,

45 at its upper end, with a cap F² in which is secured a reduced tubular valve-stem extension F³, connected at its upper end with a hollow knob G, provided at its bottom G' with outlet apertures G², as plainly indicated in Figs. 1 and 3. The knob G is adapted to be taken hold of by the operator to lift the valve F off its seat D whenever it is desired to discharge the contents of the bath tub, basin or other fixture C.

55 On the valve-stem F', immediately below the cap F², are formed overflow openings F⁴,

and near the upper end of the valve-stem extension F³ is formed a valve seat F⁵, on which is seated a ball valve H for normally closing the said extension stem F³, the top 60 of which is provided with a cap I having small apertures I' for the escape of air from the valve-stem extension F³ whenever the valve H is lifted off its seat, the said cap I also preventing the ball valve H from accidentally leaving the upper end of the valve-stem extension F³. The valve-stem extension F³ passes through a stuffing-box J arranged on the bottom of a closure K, preferably in the form of a hollow plug screwed 70 into the upper end of the stand-pipe A, so as to close this upper end of the stand-pipe. The top of the closure K is provided with upwardly-extending lugs K', on which the bottom G' of the knob G is normally seated, 75 and in the top of the closure K is formed an opening K² for the passage of a guide L, screwed or otherwise secured on the valve-stem extension F³, the guide L normally extending down into the plug K, as plainly indicated in Fig. 1.

80 The guide L is provided, at diametrically opposite points, with wings L' extending the length of the guide and passing through recesses K³ formed in the wall of the opening K², as plainly shown in Figs. 1 and 2. By the arrangement described, the valve-stem extension F³, the stem F' and the valve F are guided, in their up and down movement, to insure at all times a proper seating of the 90 valve F on the valve seat D.

85 By closing the stand-pipe A at the upper end and providing a stuffing-box J for the passage of the valve-stem extension F³, it is evident that any air or gases rising in the stand-pipe cannot escape unless the valve H is lifted off its seat.

95 As indicated in Fig. 1, the cap I for the valve-stem extension F³ is arranged within the hollow knob G, and it is evident that 100 when the valve F is seated on the valve-seat D and water passes into the fixture C, then water also rises within the stand-pipe A, and in doing so compresses the air in the upper portion of the stand-pipe, and this compressed air passes by way of the vent openings 105 F⁴ into the tubular valve-stem F', from which the air passes up through the extension F³, to lift the valve H off its seat, and consequently 110 to permit the air to pass out through the openings I' in the cap I, and by way of the hollow knob G and openings G² to the outer

- air. Thus, by the arrangement described the water passing into the stand-pipe A can rise freely therein with the water accumulating in the fixture C. It is understood that compressed air in a fixture is liable to force the usual trap or water seal in the waste pipe E and in such an event the foul gases from the sewer readily pass through the fixture into the room.
- 10 It is understood that when the water rises in the stand-pipe A, the air passes up through the valve-stem extension F³ and past the valve H, to escape by way of the cap I and the knob G, and as soon as the air has escaped, the valve H immediately seats itself on its seat F⁶. When it is desired to discharge the water from the fixture C, then the operator pulls on the knob G, to lift the valve F off its seat D, and when this takes 15 place the water can readily flow from the waste-pipe B and the stand-pipe A down into the waste-pipe E and to the sewer or other place of discharge.
- In practice, the operator pulls the knob G upward until the lower end of the guide L has cleared the top of the closure K, and then the operator gives a quarter-turn to the knob G, so as to seat the lower ends of the wings L' on the top of the closure K. By 20 this arrangement the valve F is held off its seat without the operator being compelled to hold on to the knob G. When it is again desired to close the valve-seat D, then the operator turns the knob G back to the previous 25 position, so that the wings L' register with the recesses K³, and then the knob G, extension stem F³, stem F' and valve F are allowed to drop down to their normal position for the valve F to close the valve-seat D.
- 40 From the foregoing it will be seen that foul air rising in the stand-pipe A cannot escape therefrom into the room, owing to the upper end of the stand-pipe A being closed by the closure K and the opening in the valve-stem 45 extension F³ being closed by the valve H, the latter only opening on pressure of compressed air rising within the stem F³.
- The device is very simple and durable in construction and composed of comparatively 50 few parts, not liable to get easily out of order. By using different sized plugs K, the device may be readily applied to stand-pipes of different diameters already in use on fixtures of the kind referred to.
- 55 Having thus described our invention, we claim as new and desire to secure by Letters Patent:—
1. A waste for bath tubs, basins and like fixtures, comprising a stand-pipe having a connection with the fixture and a valve-seat, a valve adapted to be seated on the said valve-seat and having a hollow stem provided near its upper end with an overflow opening and with a reduced hollow extension, a closure for the said stand-pipe and

provided with a stuffing-box for the said valve-stem extension to slide in, and a valve in the said valve-stem extension adapted to open outwardly on pressure coming up the said valve-stem and its extension. 70

2. A waste for bath tubs, basins and like fixtures, comprising a stand-pipe having a connection with the fixture and a valve-seat, a valve adapted to be seated on the said valve-seat and having a hollow stem provided near its upper end with an overflow opening and with a reduced hollow extension, a closure for the said stand-pipe and provided with a stuffing-box for the said valve-stem extension to slide in, a valve in the said valve-stem extension adapted to open outwardly on pressure coming up the said valve-stem and its extension, and a hollow knob for the upper end of the said valve-stem extension, the knob having escape 80 openings. 75

3. A waste for bath tubs, basins and like fixtures, comprising a stand-pipe having a connection with the fixture and a valve-seat, a valve adapted to be seated on the said valve-seat and having a hollow stem provided near its upper end with an overflow opening and with a reduced hollow extension, a closure for the said stand-pipe and provided with a stuffing-box for the said valve-stem extension to slide in, a valve in the said valve-stem extension adapted to open outwardly on pressure coming up the said valve-stem and its extension, a hollow knob for the upper end of the said valve-stem 90 extension, the knob having escape openings at its under-side, and means for supporting the knob spaced from the said closure. 95

4. A waste for bath tubs, basins and like fixtures, comprising a stand-pipe having a connection with the fixture and a valve-seat, a valve adapted to be seated on the said valve-seat and having a hollow stem provided near its upper end with an overflow opening and with a reduced hollow extension, a closure for the said stand-pipe and provided with a stuffing-box for the said valve-stem extension to slide in, a valve in the said valve-stem extension adapted to open outwardly on pressure coming up the said valve-stem and its extension, and a guide on the said valve-stem extension having wings extending through grooves, the said guide and its wings having a sliding engagement with the said closure. 105 110

5. A waste for bath tubs, basins and like fixtures, comprising a stand-pipe having a connection with the fixture and a valve-seat, a valve adapted to be seated on the said valve-seat and having a hollow stem provided near its upper end with an overflow opening and with a reduced hollow extension, a closure for the said stand-pipe and provided with a stuffing-box for the said valve-stem extension to slide in, a valve in the said 125 130

valve-stem extension adapted to open outwardly on pressure coming up the said valve-stem and its extension, and a guide on the said valve-stem extension having wings extending through grooves, the said guide and its wings having a sliding engagement with the top of the said closure, the lower ends of the said wings being adapted to rest on the top of the closure to hold the valve off its seat.

6. A waste for bath tubs, basins and like fixtures comprising a stand pipe having a connection with the fixture and a valve seat, a hollow waste valve adapted to be seated on the said valve seat and controlling the outflow of the water from the fixtures and also forming an overflow for the water rising in the fixture and stand pipe, the said hollow waste valve being extended through the closed upper end of the stand pipe to allow opening and closing of the hollow waste valve from the outside of the stand pipe, and an automatic device for venting the upper closed end of the stand pipe of compressed air and for normally closing the said waste valve extension to prevent the passage of foul air into the room in which the fixture is located.

7. A waste for bath tubs, basins and like

fixtures comprising a stand pipe having a 30 connection with the fixture and a valve-seat, a hollow waste valve adapted to be seated on the said valve seat and controlling the outflow of the water from the fixture and also forming an overflow for the water rising 35 on the fixture and stand pipe, the said hollow waste valve being extended through the closed upper end of the stand pipe to allow opening and closing of the hollow waste valve from the outside of the stand pipe, and 40 a self-closing valve in the extended portion of the said hollow waste valve and arranged to relieve the stand pipe of compressed air in filling the fixture with water, to prevent forcing of the trap in the waste pipe and 45 allowing the overflow to function properly; the said self-closing valve being normally in a closed position to prevent the escape of foul air rising in the said waste valve, and stand pipe. 50

In testimony whereof we have signed our names to this specification in the presence of two subscribing witnesses.
